UNITED STATES PATENT OFFICE.

AUGUST R. LUSCHKA, OF CHICAGO, ILLINOIS, ASSIGNOR TO MOTOR SPECIALTY MANUFACTURING COMPANY, OF CHICAGO, ILLINOIS, A CORPORATION OF SOUTH DAKOTA.

SPARK-COIL.

No. 877,656.

Specification of Letters Patent.

Patented Jan. 28, 1908.

Application filed October 29, 1906, Serial No. 341,005. Renewed June 22, 1907, Serial No. 380,241.

To all whom it may concern:

Be it known that I, AUGUST R. LUSCHKA, a citizen of Switzerland, and a resident of Chicago, in the county of Cook and State of Illinois, have invented certain new and useful Improvements in Spark-Coils, of which the following is a specification.

This invention relates to inductive coils, and more especially to that type of such coils known as ignition spark coils, and has for its object to provide a simple and efficient structural arrangement of the coil parts whereby leakage between the secondary winding of the coil and the condenser is prevented in a very effective manner, with a corresponding increase in the effectiveness of the apparatus, and in the durability of the component parts thereof, all as will hereinafter more fully appear.

20 In the accompanying drawings:—Figure 1, is a diagram view of an ignition spark coil system, to which the present invention is more especially applicable. Fig. 2, is a longitudinal section of an ignition spark coil, constructed in accordance with the present invention. Figs. 3, 4 and 5, are transverse sections of the same, on line $x-x$ Fig. 2, illustrating various modified arrangements of the condenser with relation to the inductive coils.

Similar numerals of reference indicate like parts in the several views.

Referring to the drawings, 1 represents the soft iron core, surrounded by the primary coil or winding 2, of comparatively heavy wire and few turns.

3, is the secondary coil or winding, of fine wire and many turns, surrounding the primary coil 2, and insulated therefrom by the usual sleeve 4, of insulating material. Usually such secondary coil 3, will be wound in two sections connected together in series as shown in Fig. 2.

5, is the inclosing casing of any suitable insulating material, and in and upon which the coil parts and accessories are mounted as usual in the present class of apparatus.

6, is the vibratory circuit interrupter, having an adjustable screw or contact 7, carried by a bracket piece 8 attached in an insulated manner to the casing 5, and provided with a binding post 9, which is in connection with a timer 10 adapted to open and close the circuit at the proper times.

55 11, is a binding post connected through

the battery 12, to the ground or engine frame, and with the low tension end of the secondary coil or winding 3, as shown.

13, is a binding post connecting with the high tension end of the secondary coil or winding 3, and connecting the same with the spark plug or other terminal where the high tension current is to be used.

14, is the condenser, arranged within the casing 5, alongside the secondary coil or winding 3, and separated therefrom by an insulating partition 15, of glass, hard rubber or like insulating material; such condenser is connected in shunt with the circuit of the automatic interrupter 6, and as so constructed and arranged the end of the secondary coil or winding next to the interrupter will be the ground side of such coil, while the other end will be the high tension side of said coil.

The construction and arrangement of parts so far described, is common to ignition spark coils in general use, and is intended to illustrate an application of the present improvement to spark coils equipped with vibratory interrupters; the present improvement is however applicable to any other type of spark coils where the arrangement and location of the condenser remains the same, as for instance the ordinary type of coil without an interrupter, often used.

As usually arranged the condenser 14, extends the entire length of the coil, and I have found that regardless of the insulating partition 15, or other equivalent insulating means, there is a considerable discharge of high voltage electricity from the high tension side or section of the secondary coil or winding 3, to the condenser, along the entire length of such section of the secondary coil, and which discharge materially reduces the quantity of current obtained at the terminal 13 of the apparatus. Such discharge, while in the nature of a silent discharge, has the tendency to destroy the insulating materials used in course of time, and which once broken through renders the coil absolutely useless.

With the purpose of remedying the defects above pointed out, the present improvement consists in the construction of the condenser 14, of a length approximating that of the low tension section of the secondary coil or winding 3, and the arrangement of the condenser so formed in an adjacent relation to said section of the secondary coil, as illus-

trated in Fig. 2. By such formation and arrangement, the preservation of the insulating partition 15 is attained in a very perfect manner, while the apparatus is rendered 5 much more powerful and certain, due to an entire elimination of internal leakage.

In the practical application of the present invention, the condenser 14 may be of the flat form shown in Fig. 3 and arranged beneath the secondary coil or winding 3; or the said condenser may be made of an angular form to partially encircle the secondary coil or winding, as illustrated in Fig. 4; or said condenser may be of an annular form and 15 adapted to fully or partially encircle said secondary coil or winding as illustrated in Fig. 5, and as the particular requirements or the judgment of the constructor may dictate.

Having thus fully described my said invention what I claim as new and desire to secure by Letters Patent, is:—

1. In a spark coil of the type described, the combination of a secondary coil or winding, and a condenser arranged at the low tension or grounded end of said secondary coil.

2. In a spark coil of the type described, the combination of a secondary coil formed with high and low tension sections, and a condenser arranged adjacent to the low tension section of said secondary coil.

3. In a spark coil of the type described,

the combination of a secondary coil or winding having a low tension end formed by a ground connection through the battery, and a condenser arranged at said low tension end.

4. In a spark coil of the type described, the combination of a secondary coil or winding, and a condenser of an annular shape encircling said coil and arranged at the low tension end thereof.

5. In a spark coil of the type described, the combination of a secondary coil formed with high and low tension sections, and a condenser of an annular shape encircling the low tension section of the secondary coil.

6. In a spark coil of the type described, the combination of a secondary coil or winding having a low tension end formed by a ground connection through the battery, and a condenser of an annular shape encircling said coil and arranged at the low tension end thereof.

7. In a spark coil of the type described, the combination of a secondary coil wound in a plurality of sections and a condenser arranged adjacent to the grounded side of said secondary coil.

Signed at Chicago, Illinois, this 25th day of October 1906.

AUGUST R. LUSCHKA.
